Primary Examiner — Carla Jobe Wright(74) *Attorney, Agent, or Firm* — Birch, Stewart, Kolasch & Birch, LLP(57) **CLAIM**

The ornamental design for a case for cellular phone, as shown and described.

DESCRIPTION

FIG. 1 is a front, right side, perspective view of a case for cellular phone showing our new design; and

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, right side, perspective view thereof, shown in a state of use with an environmental cellular phone.

The broken lines in FIG. 8 depict an environmental cellular phone that forms no part of the claimed design.

1 Claim, 4 Drawing Sheets(56)
